UNITED STATES PATENT OFFICE

HENRY J. HANZLIK, OF SWARTHMORE, PENNSYLVANIA, ASSIGNOR TO WESTINGHOUSE ELECTRIC & MANUFACTURING COMPANY, A CORPORATION OF PENNSYLVANIA

TURBINE

Application filed November 27, 1926. Serial No. 151,105.

My invention relates to elastic fluid turbines, and it has for its object to improve the operation and control thereof, more particularly to prevent overspeeding of the turbine upon a sudden dropping of its load.

In large turbine installations it has been found that overspeeding results upon a sudden dropping of the load on the turbine. While the governing mechanism operates promptly to close the admission valve and turn off the supply of motive fluid to the turbine, there may be stored within the casing large quantities of motive fluid under pressure, and this fluid, in expanding, acts upon the rotor and causes an overspeeding or racing thereof. For example, the fluid in the high-pressure turbine of a compound turbine installation must pass through the low-pressure turbine to expand, and in doing so, it may act upon the low-pressure turbine.

One of the spaces in which motive fluid has collected is the space between the blade carrying portion of the blade ring and the casing, or between the annular blade rows and the casing. Another is the space between the dummy piston and the casing. In accordance with my invention I fill these spaces to prevent a storing of motive fluid therein.

Apparatus embodying my invention is illustrated in the accompanying drawing in which:

Fig. 1 is a longitudinal section through a turbine; and,

Fig. 2 is a section of a blade ring taken along the line II-II of Fig. 1.

Referring to the drawing in detail, I show a turbine 10 including a casing 11 and a rotor 12. Placed within the casing are blade rings or blade holding members 13. The blade holding members comprise an inner peripheral wall 21, in which the stationary blades 17 are fastened, an outer peripheral wall or portion 22, and side walls 23 and 24 connecting the adjacent ends of the peripheral walls 21 and 22. These walls define a space which is substantially fluid tight.

One of the walls, preferably the outer peripheral wall, is provided with some means for securing the ring member in the

casing, such means being shown in the present drawing as a flange 16 interlocking in a groove 15 in the casing.

As indicated in the drawing, these filler rings are so shaped that they occupy substantially the entire space between the blade space and the casing, only sufficient space being allowed to provide for unequal expansion and ready assembly of the parts.

In order to allow the hollow space within the rings to attain approximately the pressure on the outside of the rings, I may provide small openings 20. These openings are of such restricted size, however, that fluid cannot escape therethrough rapidly enough to race the rotor.

The dummy packing rings 14 are similarly constructed, comprising the peripheral walls 21 and 22 and the side walls 23 and 24. These rings carry the stationary elements of the packing 18, cooperating with the packing elements carried by the dummy piston 29. The rings 14 fill up practically all the space between the dummy piston packing and the casing.

Internal stiffening ribs or reinforcing webs 19 may be formed in the hollow portions of the rings around the circumference thereof. As shown in Fig. 2, the ring may be made in halves, secured together in any desired manner. Preferably the halves are formed with flanges 26 at their ends and with recesses 25 adjacent thereto, to accommodate bolts 27 and nuts 28 which clamp the flanges 26 together.

From the above description, it will be apparent that I have reduced the spaces within the turbine in which motive fluid may be stored and that accumulations of motive fluid are thereby avoided. Upon closing of the admission valve, the small amount of motive fluid within the turbine is quickly expanded before racing the turbine.

It will also be apparent that the turbine will respond more rapidly to actions of the governor. Upon an opening movement of the admission valve by the governor, the increased amount and pressure of the motive fluid will immediately act upon the blades instead of accumulating in dead spaces.

Upon decreased opening of the admission valve, the power output will immediately drop instead of being maintained by accumulated motive fluid.

5 While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

10 15 I claim as my invention:

1. In a turbine, the combination with a casing and a rotor spaced interiorly thereof, of annuli of members encircling the rotor and hollow filler rings each supporting a plurality of said annuli and substantially filling the space between the annuli and the casing, whereby accumulations of motive fluid in the casing are avoided.

2. In a turbine, the combination with a casing and a rotor spaced interiorly thereof, of annuli of members encircling the rotor and hollow filler rings disposed in juxtaposed relation and substantially filling the space between the annuli and the casing, whereby accumulations of motive fluid in the casing are avoided, each of said hollow filler rings spanning a plurality of said annuli.

3. A turbine including a casing, a rotor disposed therein and having blades secured thereto, and a hollow blade-carrying ring or rings carrying blades cooperating with the rotor blades, said ring or rings spanning a plurality of rows of blades and occupying substantially all the space between the blades carried thereby and the casing, and said hollow space being substantially fluid tight.

4. A turbine including a casing, a rotor disposed therein carrying dummy packing elements, and a dummy ring or rings which carry cooperating dummy packing elements and which occupy substantially all the space between the dummy packing elements and the casing.

5. A blade ring comprising a blade-holding portion at its inner periphery, a portion for attachment to the casing at its outer periphery, and spaced connecting walls between said two peripheral portions, the space between the walls being substantially fluid tight.

6. A blade ring comprising a blade-holding portion at its inner periphery, a portion for attachment to the casing at its outer periphery, and a hollow connecting portion between said two peripheral portions, the hollow space being substantially fluid tight.

7. A blade-holding ring member comprising an inner peripheral blade-carrying wall,

an outer peripheral wall having a flange for attachment to the casing, and side walls connecting the adjacent ends of the peripheral walls.

8. A turbine including a casing, a rotor and a ring member disposed in the casing, said ring member comprising an inner peripheral wall having elements extending from the wall, an outer peripheral wall adjacent to casing, and side walls connecting the adjacent ends of the peripheral walls.

9. A turbine including a casing, a rotor and a ring member disposed in the casing, said ring member comprising an inner peripheral wall having elements extending toward the rotor, an outer peripheral wall adjacent to casing having a flange engaging in a groove in the casing, and side walls connecting the adjacent ends of the peripheral walls.

10 15 In testimony whereof, I have hereunto subscribed my name this 15th day of November, 1926.

HENRY J. HANZLIK.
